UNITED STATES PATENT OFFICE.

CHARLES WESLEY BLAKE, OF NORFOLK, VIRGINIA.

SHIP'S WINDLASS.

SPECIFICATION forming part of Letters Patent No. 781,487, dated January 31, 1905.

Application filed March 15, 1904. Serial No. 198,240.

To all whom it may concern:

Be it known that I, CHARLES WESLEY BLAKE, a citizen of the United States, and a resident of Norfolk, in the county of Norfolk and State of Virginia, have invented new and useful Improvements in Ships' Windlasses, of which the following is a full, clear, and exact description.

This invention relates to hoisting devices; and it consists, substantially, in the construction and combinations of parts hereinafter particularly described, and pointed out in the claims.

The invention has reference more especially to windlasses, hoisting-drums, winches, capstans, towing-machines, steering-gears, and other similar devices employed on a ship or other marine vessel; and the principal object thereof is to provide means for overcoming or neutralizing the effects of pulls or strains upon the anchor chains or cables, hawser chains or cables, or other chains or cables of the vessel caused by undue surging of the vessel produced by motion of the sea, more especially when the vessel is at anchor, or when the anchor is being weighed, or when the vessel is being towed in a heavy sea or swell.

The invention also has additional objects in view, as will hereinafter more fully appear, when taken in connection with the accompanying drawings, forming a part of this specification, in which similar characters of reference indicate corresponding parts in all the figures.

Figure 1 is a view in perspective of a hoisting device, as a ship's windlass, having my improvements embodied in connection therewith.

Fig. 2 is a vertical transverse sectional elevation thereof to more clearly indicate the construction and operation of parts. Fig. 3 is a detail sectional view taken on the line 3-3 of

Fig. 2; and Fig. 4 is a top plan view representing more clearly the organization of the driving-worm for the windlass and the reacting cushioning devices therefor serving to relieve strain on working parts of the structure.

Specific reference being had to the drawings by the designating characters marked thereon, 1 represents a portion of the deck of a ship or other vessel, to which is secured in any suit-

able manner a base or bed plate 2, standing upwardly from the ends of which are bearings, such as 3, for the support of the main shaft 4 of an ordinary ship's windlass, said shaft having thereon the power-wheel 5, on either side 55 of which is loosely mounted on the shaft a wildcat or drum 6 for an anchor or other chain or hawser 7, engaged by lugs 8 on said wildcat, the latter, as is common in windlasses of this kind, being provided with some suitable device (not shown) by which it may be locked to the shaft whenever desired to cause heaving in of the chain or hawser; but when the wildcat is unlocked from said shaft the chain or hawser may be let out at will under the action 60 of the usual brake, comprising in the present instance a pulley 9 and a friction-band 10, said brake being controlled by an ordinary operating-lever, (not shown,) as is well understood.

To the deck of the vessel are rigidly secured suitable blocks 12, disposed a proper distance apart beyond the power-wheel 5, said blocks being provided with bearing-boxes 13 for the support of the relatively long rotatable driving-shaft 14, disposed substantially 65 at right angles to the shaft 4 beneath and in practically vertical alignment with said wheel 5, said shaft 14 being driven from any suitable engine or source of power. (Not shown.) Said blocks and bearing-boxes are preferably 70 located to the front and rear of the power-wheel 5 and in line therewith; but if the character of work to be performed by the structure requires it the driving-shaft 14 may be supported in a frame (see Fig. 4) comprising 75 the transverse bars 15 15 and the side beams 16 16, connecting said bars, said shaft passing through suitable bores or openings therefor in said transverse bars.

Mounted upon the driving-shaft 14 is a tubular worm gear or shaft 17, which is keyed to the shaft 14 through the medium of a key or spline 18, the construction being such that longitudinal movement of said worm-gear on the said driving-shaft is permitted. It will 90 be observed, Figs. 1 and 2, that the said tubular worm-gear meshes with the cogs 11 of the power-wheel 5, so that when the shaft 14 is driven the revolution of the worm-gear therewith will impart motion to the power- 95 100

wheel and drive the shaft 4, thereby causing a turning of the wildcat or drum 6 for the purpose of winding up the chain or hawser 7. Now, as is well known, the surging or dipping of the vessel often causes a jerking or pulling strain to be placed upon the chain or hawser, especially when the vessel is at anchor or when a heavy swell is on, and this frequently causes breaking or parting of the chain or damage to the various parts of the windlass or machine, especially when the driving-gear is entirely rigid. This is obviated by having the tubular worm gear or shaft slideable upon the driving-shaft 14, and in order to tension the movement of such worm along the driving-shaft 14 I employ a coil-spring, such as is shown at 20, about the same, between one of the frame pieces or blocks 12 and the adjacent end of the worm gear or shaft, it being understood that the latter is shorter than the length of the driving-shaft 14 between the said blocks 12. In order to protect the ends of the spring from being injured and to render the working of the machine easy, I place a washer 20^x between the end of such spring and the adjacent end of the tubular worm-shaft; but if extremely heavy work is to be performed with the machine or windlass it will necessitate, perhaps, a plurality of tension-springs, in which case I arrange a bar 22 transversely of the frame, as seen in Fig. 4, in such manner that the bar may slide upon the side pieces 16 16 of said frame, the shaft 14 passing through an aperture or hole bored centrally in such bar, the construction being such that the bar will lie between the tubular worm-shaft and the adjacent end of the central spring 20^a, additional tension-springs 20^b 20^c being coiled about the side bars 16 16 between the sliding bar 22 and one of the transverse bars 15.

From the above description, taken in connection with the accompanying drawings, the construction and operation of my improved machine will be readily apparent. When any unusual or unexpected strain is placed upon the chain or hawser, such as will cause the same to move with the wildcat, and consequently revolve the power-wheel backward, such power-wheel will force the loosely-keyed worm gear or shaft backward against the tension of the spring or springs, and when the strain is relieved such spring or springs expand to their normal position and push the said worm gear or shaft again to its normal position. Heretofore when the power-wheels started to revolve under such strain the parts of the machine being rigid the surge of the vessel generally caused the breaking of the chain or the stripping of the threads of the worm gear or shaft or the breaking of the teeth of the power-wheel; but it will be noted all this is obviated by the mechanism herein described. If for any reason it should not be desired to employ the tension spring or

springs, the tubular worm gear or shaft may be keyed up rigidly with the driving-shaft 14 through the medium of a pin 23, as shown in Fig. 3, which pin passes through apertures in the tubular worm gear or shaft and through a bore which extends diametrically through the shaft 14.

While I have herein shown and described one preferred embodiment of my invention, I wish it to be understood that I do not consider myself as limited to all the precise details of construction shown herein, as there may be modifications and variations in several respects without departing from the essential features of the invention or sacrificing any of the advantages thereof. For instance, instead of employing tension-springs, as herein described, I may make use of any suitable yielding device which will perform the function of returning the sliding tubular worm gear or shaft to its normal position after such shaft has been dislodged therefrom through the revolution of the power-wheel. There are many advantages incident to my improved mechanism other than those herein enumerated; but they will be obvious to those acquainted with mechanisms of this sort, so that it is unnecessary to further elucidate the same.

Having thus described my invention, I claim as new and desire to secure by Letters Patent—

1. In mechanism of the class described, the combination with a gear-wheel, of driving mechanism therefor, comprising a driving-shaft arranged adjacent to said gear-wheel, a tubular worm-shaft slideable on said driving-shaft and rotatable therewith, a fixed stop against which one end of said worm-shaft abuts, a sliding member on the drive-shaft arranged to abut the other end of the tubular worm-shaft, and said sliding member being spring-pressed to hold it normally against said worm-shaft.

2. In mechanism of the class described, the combination with a rotatable shaft, a winding-drum fixed on said shaft and a gear-wheel also fixed on said shaft, of a driving-shaft arranged adjacent to said gear-wheel, a tubular worm-shaft slideable on said driving-shaft and rotatable therewith, a fixed stop against which one end of said worm-shaft abuts, and a spring received upon the other end of said worm-shaft to hold it normally against said stop.

3. In mechanism of the class described, the combination with a rotatable shaft, a hoisting-drum carried by said shaft, and a gear-wheel also carried by the shaft, of a driving-shaft arranged adjacent to the gear-wheel, a tubular worm-shaft slideable on the driving-shaft and rotatable therewith, a stop at one end of said worm-shaft, a transverse bar slideable on said driving-shaft and engaging one end of said worm-shaft, and a plurality of springs engaging said bar to hold it against the end of said worm-shaft.

4. In mechanism of the class described, the combination with a rotatable shaft, a hoisting-drum carried by said shaft, and a gear-wheel also carried by the shaft, of a driving-shaft disposed adjacent to said gear-wheel, a tubular worm-shaft slidable on the driving-shaft and rotatable therewith, a stop against which one end of said worm-shaft abuts, a pair of guide-rods disposed parallel with and on opposite sides of said driving-shaft, a transverse bar or block slidable on said guide-rod and contacting with the end of the worm-shaft opposite the stop, and a plurality of springs carried by said driving-shaft and said guide-rods, said springs engaging said transverse bar or block to press it forcibly against the end of the worm-shaft.
5. In a mechanism of the class described, the combination of a frame, a shaft journaled

therein, a hoisting apparatus carried by said shaft, a cog-wheel mounted on the shaft, a driving-shaft revolubly mounted in bearings adjacent to the cog-wheel, a tubular worm-shaft keyed to the driving-shaft in such manner that it is rotatable therewith and movable longitudinally thereof, and means passing through the worm-shaft and driving-shaft for holding the aforesaid worm-shaft against longitudinal movement on the driving-shaft, substantially as set forth.

In testimony whereof I have signed my name to this specification in the presence of two subscribing witnesses.

CHARLES WESLEY BLAKE.
